UNITED STATES PATENT OFFICE.

JOHN R. BOYLE, OF BELOIT, WISCONSIN.

TOILET-PAPER HOLDER.

1,226,453.

Specification of Letters Patent.

Patented May 15, 1917.

Application filed November 20, 1915. Serial No. 62,608.

To all whom it may concern:

Be it known that I, JOHN R. BOYLE, a citizen of the United States, residing at Beloit, in the county of Rock and State of Wisconsin, have invented new and useful Improvements in Toilet-Paper Holders, of which the following is a specification.

This invention relates to a toilet paper holder adapted for connection with the seat post of a closet.

The primary object of the invention is to provide a toilet paper holder of the class described which has a horizontally movable roll holding member which, enables the roll of toilet paper connected therewith to be positioned within convenient reach of the person using the closet.

A still further object of the invention is to provide a toilet paper holder which may be connected with the various types of closets now in use by means of the seat post thereon thus, obviating the necessity of boring holes in the wall of the toilet room to enable the holder to be connected with the wall.

With these and other objects in view the invention resides in the novel combination and arrangement of parts which will be hereinafter described and more particularly pointed out in the claim.

The preferred embodiment of the invention has been illustrated in the accompanying drawing, also no restriction is necessarily made as to the precise details of construction therein shown, as changes, alterations and modifications within the scope of the appended claim may be resorted to when so desired.

Like characters of reference denote corresponding parts throughout the several views in the drawings in which—

Figure 1 is a top plan view of a closet showing the invention connected to the seat post thereon,

Fig. 2 is a perspective view of the toilet paper holder removed from the seat post,

Fig. 3 is a sectional view disclosing the means connecting the roll holder with the supporting arm,

Fig. 4 is a detailed sectional view to more clearly illustrate the connection of the roll retaining means with the rod constituting a part of the holder.

Referring now to the drawing in detail the numeral 1 designates a closet of the ordinary well known construction which is

provided with the usual seat 2, which is hingedly connected with a seat post 3 extending vertically through the rim of the closet at the rear end thereof, said seat post 60 being secured to the rim of the closet by means of the usual nut 4.

The improved toilet paper holder is designated by the numeral 5 and comprises a supporting arm 6 and a roll holder 7. The 65 supporting arm 6 has each end thereof flattened and provided with an eye 8, said arm also having between the ends thereof an offset portion 9, whereby a portion of said arm may be disposed above the seat 2. 70

With reference to Fig. 2 in the drawing it will be seen that one flattened end of the supporting arm 6 is considerably larger than the other flattened end of the arm which is designated by the numeral 10, said 75 first mentioned end of the arm being adapted to contact with the under side of the rim of the closet 1 when the seat post 3 has its lower end passed through the opening in the end of the arm and the nut upon the 80 seat post frictionally engaged with said flattened end of the arm, so that the arm may be turned in a plane parallel with the seat.

From the foregoing statement it will be seen that by loosening the nut 4 the supporting arm 6 may be moved horizontally with relation to the closet 1 and retained in any desired position when the nut 4 is tightened thereagainst.

The roll holder 7 comprises a rod 11, a 90 flanged cylinder 12 fixed to the rod and a roll retaining member 13.

The rod 11 has the end thereof distant from the cylinder 12 flattened as indicated by the numeral 14 and provided with an 95 aperture 15, said flattened end being adapted to contact with and underlie the flattened end of the supporting arm 6, so that a bolt 17 may be passed through the openings in the flattened ends of the supporting arm 100 and rod and have threadedly connected therewith a wing nut 18 adapted to bear on the end 10 of the supporting arm 6 and in this manner cause said flattened ends to be held in frictional contact yet permitting the 105 rod to be turned in a plane parallel with the supporting arm 6.

The remaining end of the rod 11 which extends beyond the cylinder 12 is threaded and has threadedly engaged therewith the 110 roll retaining member 13 having an enlargement 19 by means of which said roll retain-

ing member may be removed from the threaded end of the rod 11 to enable a roll of toilet paper to be positioned upon the cylinder 12.

5 With reference to Fig. 1 in the drawing it can readily be seen that through the use of the bolt 17 and the wing nut 18, the nut 18 can be adjusted upon the bolt to permit the roll holder to be moved horizontally 10 away from, or toward the closet 1, as the occasion may require, and maintained in any position desired, while through adjustment of the nut 4 on the seat post 3, the arm 6 can also be adjusted with relation to the 15 closet 1 and connected with the rim thereof upon either side of the closet.

From the foregoing statements taken in connection with the accompanying drawing it is at once apparent that a toilet paper 20 holder has been provided, which is simple

in construction, inexpensive of manufacture and highly efficient in use.

Having thus described the invention what is claimed as new is:—

A toilet paper holder comprising a sectional arm adapted to be adjustably pivoted upon the seat post of the toilet seat, one of said sections comprising a horizontal portion, an integral vertical portion, a second integral horizontal portion, the second section comprising a horizontal portion pivoted to swing horizontally upon said first mentioned section and a cylinder carried by the opposite end of the second section.

In testimony whereof I affix my signature in presence of two witnesses.

JOHN R. BOYLE.
